United States Patent

Des. 240,406
Patented July 6, 1976

240,406

HAND FOR A WATCH

Paulette G. Kelman, 19264 Pacific Coast Highway,
Malibu, Calif. 90265

Filed Nov. 27, 1970, Ser. No. 26,203

Term of patent 14 years
The term of this patent subsequent to Dec. 6, 1988,
has been disclaimed

Int. Cl. D10—07

U.S. Cl. D10—127

FIG. 1

FIG. 2

FIG. 3

FIG. 4

FIG. 1 is a planar view of a hand for a watch, showing my new design;

FIG. 2 is a side elevational view of FIG. 1;

FIG. 3 is a planar view of another embodiment of a hand for a watch, showing my new design; and

FIG. 4 is a side elevational view of FIG. 3.

I claim:

The ornamental design for a hand for a watch, as shown and described.
